UNITED STATES PATENT OFFICE

104,980

DESIGN FOR A SUIT

Salvatore Lo Prete and Vincenzs Lo Prete, New York, N. Y.

Application May 11, 1937, Serial No. 69,297

Term of patent 3½ years

To all whom it may concern:

Be it known that we, Salvatore Lo Prete and Vincenzs Lo Prete, citizens of the United States of America, residing in New York, county of New York, and State of New York, have invented a new, original, and ornamental Design for a Suit, of which the following is a specification, reference being had to the accompanying drawing, forming part thereof, wherein,

We claim:

The ornamental design for a suit, substantially as shown.

SALVATORE LO PRETE.
VINCENZS LO PRETE.
